UNITED STATES PATENT OFFICE.

EDWYN HILL, OF SAN ANTONIO, TEXAS.

HAMPER.

1,141,638.

Specification of Letters Patent.

Patented June 1, 1915.

Application filed July 10, 1914. Serial No. 850,201.

To all whom it may concern:

Be it known that I, EDWYN HILL, a citizen of the United States, residing at San Antonio, in the county of Bexar and State of Texas, have invented a new and useful Hamper, of which the following is a specification.

The present invention appertains to hampers, and is particularly an improvement 10 over the parcel post hamper disclosed in my copending application filed February 14, 1914, Serial No. 818,741.

It is the object of the present invention to provide a hamper adapted particularly for 15 transporting parcel post packages, or which may be employed by express companies, bakeries, laundries and the like, to fulfil the needs of a device of the present character.

It is the specific object of the present invention to provide a hamper of novel and improved construction, whereby the same may be compactly collapsed, when not in use, for purpose of ready storage and shipment, the hamper being provided with unique 25 means for holding the same in open or package-receiving position.

It is also within the scope of the present invention to reduce the construction of the device to the utmost simplicity and cheapness, consistent with the convenience, serviceability and efficiency of the device. 30

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 40 within the scope of what is claimed, without departing from the spirit of the invention.

The invention has been illustrated in its preferred embodiment in the accompanying 45 drawing, wherein:—

Figure 1 is a perspective view of the hamper in extended or unfolded position. Fig. 2 is a perspective view of the hamper in folded or collapsed condition. Fig. 3 is 50 a longitudinal section of the hamper in extended condition, and Fig. 4 is a transverse section of the device in extended condition.

The hamper embodies a collapsible container or receptacle, which is preferably of 55 rectangular outline, and which includes a base or bottom 1 of suitable construction,

having a marginal upturned flange or rim 2, and the container further includes a rectangular frame or rim member 3 and fabric or flexible sides and ends 4 connecting the 60 rim member 3 and the flange 2 of the bottom 1. The sides and ends of the container are adapted to collapse to enable the rim member 3 to be placed immediately upon the bottom 1 when the device is to be folded. 65

A cover 5 is provided for the container, and is equipped with a marginal rim or flange 6 adapted to be slipped over the rim or frame member 3 of the container, to close the container. Suitable handles 7 are preferably attached to the ends of the cover 5 for enabling the hamper to be conveniently handled during its transportation. 70

As a means for holding the cover 5 in place, and for holding the container and 75 cover intact during shipment, straps 8 are passed transversely around the sides, bottom and top of the hamper, and are provided with buckles in order that the straps may be opened when the cover 5 is to be 80 removed. The cover 5 is preferably provided with strap guides 9 thereon through which the straps 8 are passed, to hold them against longitudinal shifting, and the straps 8 are preferably riveted or otherwise secured 85 to the bottom of the hamper to hold them in place.

The means for holding the container in open or unfolded condition comprises a pair of props 10 disposed within the end portions of the container. The props 10 are of skeleton or frame-like form, and each embodies a pair of upright strips or struts 11 disposed adjacent the sides of the container, and having their lower ends pivotally anchored to the bottom 1 of the container by means of hinges 12 adjacent the corresponding end of the container. Each of the props 10 also embodies a lower cross strip or bar 13 terminally riveted or otherwise 100 secured to the strips or struts 11 adjacent their lower or hinged ends, and a cross bar or strip 14 terminally riveted or otherwise secured to the strips 11 adjacent their free ends. The props 10 are of a size corresponding with the ends of the container, to fit snugly against the ends of the container when the container is in unfolded condition, with the strips or struts 11 disposed within the corners of the container. The lower 110 strips 13 of the props are adapted to engage over the ends of the rim 2 of the bottom,

while the upper strips 14 are adapted to engage under the ends of the rim member 3 when the props are swung upwardly to upright positions, as seen in Fig. 3.

5 When the device is to be folded, the props 10 may be swung inwardly and downwardly upon the bottom 1 within the rim 2 thereof, in order that the container may be folded as seen in Fig. 2.

10 Depending or pendant latches 15 are pivoted to the ends of the rim member 3, and have leather tabs or finger pieces 16 secured to their lower or free ends, whereby the latches may be conveniently swung by hand.

15 The latches 15 are adapted to be swung downwardly over the free ends of the props 10, or the cross bars 14 thereof, when the props are swung to upright position as illustrated in Figs. 3 and 4. Thus, the latches 15 serve to hold the props in erect position when the hamper is in unfolded condition.

20 In use, when the hamper is to be filled, the cover 5 is first removed, and the rim member 3 raised to distend the container. The props 10 are then swung to upright position, whereby their free end portions or cross bars 14 engage under the ends of the rim member 3, to support the rim member 30 in elevated position, and to therefore hold the container unfolded. The latches 15 may then be swung to engage over the cross bars 14, for holding the props in position, and the container may then be filled with the articles or packages to be transported, in which event, the cover 5 may be slipped over the rim member 3, and the straps 8 buckled and drawn taut to hold the cover and container intact. In this condition, the 35 hamper may be readily handled and shipped without difficulty, and without liability of fragile articles within the hamper being broken or damaged.

40 When the hamper has reached its destination, the straps 8 may be opened, and the cover 5 removed so as to enable the contents of the hamper to be discharged or taken out. The hamper may then be compactly folded so as to be inexpensively returned to the owner or shipper, and to this end, the props 10 may be folded against the bottom 1, after latches 15 have been released, and the rim member 3 may then be dropped onto the bottom 1. The cover 5 may then be applied to the rim member 3

45 and the straps 8 properly wrapped around the bottom 1 and cover 5 and buckled to bind the folded parts in compact position. The hamper may then be shipped or returned to the owner or shipper in flat or compact condition.

50 From the foregoing, taken in connection with the drawing, the other attributes and capabilities of the present invention will be obvious to those versed in the art, without further comment being necessary, it being noted that the present hamper is comparatively simple and inexpensive in construction, may be constructed in various sizes according to the circumstances and needs, and 55 is otherwise of practical merit.

Having thus described the invention, what is claimed as new is:—

1. A hamper comprising a container including a bottom, a rim member, and collapsible walls connecting them; props disposed within the container, hinged to the bottom, and having their free ends engageable with the rim member when the same is raised; and latches carried by the rim member and engageable with the free ends of the props to hold them in place.

2. A hamper comprising a container including a bottom, a rim member, and collapsible walls connecting them; props hinged to the bottom and having their free ends arranged to swing under the rim member when the rim member is raised; and latches pivoted to the rim member to swing over the free ends of the props.

3. A hamper comprising a container including a bottom, a rim member, and collapsible walls connecting them; props within the container and each including a pair of struts hinged to the bottom at the respective corners of the container, and a cross bar connecting the free ends of the struts and adapted to fit under the rim member when the rim member is raised; and latches carried by the rim member and engageable over the said cross bars to hold them in place.

95 In testimony that I claim the foregoing as my own, I have hereto affixed my signature in the presence of two witnesses.

90
EDWYN HILL.
